FACE PANEL FOR A CARD CATALOG DRAWER

Stephen F. McKeon, Utica, N.Y., assignor to
Sperry Rand Corporation, New York, N.Y.

Filed Jan. 19, 1971, Ser. No. 107,878

Term of patent 14 years

Int. Cl. D6—99

U.S. Cl. D6—192

FIG. 1.

FIG. 2.

FIG. 4.

FIG. 3.

FIG. 5.

FIG. 1 is a front view of a drawer face panel showing my design;

FIG. 2 is a side elevational view of the drawer face panel shown in FIG. 1;

FIG. 3 is a top view thereof;

FIG. 4 is a bottom view thereof; and

FIG. 5 is a front perspective view thereof.

I claim:

The ornamental design for a face panel for a card catalog drawer, substantially as shown.
